UNITED STATES PATENT OFFICE.

CLARENCE E. KING, OF SALT LAKE CITY, UTAH.

BUILDING-BLOCK MOLD.

1,409,300.

Specification of Letters Patent. Patented Mar. 14, 1922.

Application filed April 28, 1920. Serial No. 377,382.

To all whom it may concern:

Be it known that I, CLARENCE E. KING, a citizen of the United States, residing at Salt Lake City, in the county of Salt Lake and 5 State of Utah, have invented certain new and useful Improvements in Building-Block Molds, of which the following is a specification.

My invention relates to forms for molding 10 blocks of concrete, fire-clay or other plastic quickly setting material, and has for its object to provide an economical form for making building blocks for straight wall, and one with corners, windows, doors and 15 header runs.

These objects I accomplish with the device illustrated in the accompanying drawings in which similar letters and numerals of reference indicate like parts throughout 20 the several figures and as described in the specification forming a part of this application and pointed out in the appended claims.

In the drawings in which I have shown a 25 substantial embodiment of my invention, Figure 1 is a plan of the form for molding a plurality of blocks at one setting, and in which I have shown some of the different individual forms which may be used in my 30 apparatus to mold the different shaped blocks required in constructing buildings. Figure 2 is an end elevation of the block which may be molded in section A of Figure 1. Figure 3 is a plan view of the same 35 block. Figure 4 is an elevation of the other end of the same block, while Figure 5 is a side elevation of the same block. Figures 6, 7 and 8 are plan, end elevation and side elevation, respectively, of a header block 40 which may be molded in section C of the form shown in Figure 1. Figures 9, 10, 11 and 12 are end elevation, plan, opposite end elevation and side elevations respectively, of a block which may be molded in section D 45 of the form shown in Figure 1. Figures 13 and 14 are side and end elevation respectively, of the core used in the mold in sections A and B. Figures 15 and 16 are side and end elevations respectively, of the core 50 used in section B. Figures 17 and 18 are side and end elevation respectively of the core used in section C. Figure 19 is an edge and side elevation respectively of the partition block used between sections A and B. 55 Figure 20 is a side and end elevation and plan view respectively of the filling block

used in sections C and E to form the openings shown in Figures 6 and 10. Figure 21 is a side elevation and edge view of one of the partition blocks used between sections C 60 and D. Figure 22 is a side and edge view of the metal plate used contiguously with the partition blocks to give the block a finished face. Figure 23 is a side elevation and edge view of the metal plate used to 65 give the side of the blocks a finished face. Figure 24 is in a vertical transverse section on line 25 of Figure 1.

My apparatus is constructed of dimension lumber with a closed bottom 1, to the edges 70 of which are nailed or secured in any suitable way the guide strips 2. The side pieces 3 are placed but not nailed in the angled corner of 1 and 2, and each has the vertical height required in the thickness of the 75 blocks. The end pieces 4 are held in place by pins 5 which are secured in the bottom 1 and sides 3, and which engage in holes in the edges of said end pieces. The upper edges of the form are held in position by 80 the cross ties 6. The length of the blocks are determined by the cores 7, 8 or 9, different views of which are shown in Figures 13, 15 and 18. The partition members 10 and 11 are used to separate one block from 85 the other, and except on the end, header and pier blocks the filling blocks 12 are secured on one side of the said partition members. In header and pier blocks the said filling 90 blocks 12 are secured to the cores, as shown in sections B, C and E of Figure 1, to form the openings 17 in Figures 6 and 10. The openings formed in the blocks connect the longitudinally disposed openings 19 formed by the cores in one side face of all blocks. 95 The cores 7, 8 and 9 are to save material; to make the block lighter; to form a large continuous air space around the building in the wall in which they are used, and the core used in the forms works automatically 100 with the partition in setting up the form ready to fill, so that no measuring, nailing or spacing is required, as the cores 7, 8 and 9 and the partitions 10 and 11 hold each other in place and the blocks used will be the same 105 length as the core used. The filling blocks 12 when used in sections A, B and D form a hole in one end of the block which, when the block is laid in the wall, makes a vertical air space, continuously through the 110 wall in which they are laid, and they form a convenient hand-hold for the bricklayer

who lays them, allowing him to place the block contiguous the other one without mashing his hand, and it also leaves a convenient place to knock the core out of the block when stripping or removing it from the forms. The partitions may vary in size and in proportion to the block and be made of either wood, sheet or solid metal. The pieces of sheet metal 20 and 21 are cut the size of the end and side face, respectively, of the block, and are shown in Figures 23 and 24 with the edges cut at an angle, and serve the purpose of leaving good edges and a smooth surface on the block cast, and where a colored facing is desired, the facing material may be spread on the longer side of the sheet metal and placed in the face of the forms before the body of the block is poured, so that when the form is filled the block with facing as desired is made in the same cast.

My forms are intended to be used in casting building blocks for foundations, outside walls, or inside partition walls, composed of concrete, brick or fire-clay, terra cotta, or any cement or plastic material. While the form shown and illustrated in the accompanying drawings, indicates but one size block to be cast, it is intended, by using different dimension lumber for the forms, to make any size block or brick desired, with any size core-opening desired. The cores may be made of either wood or metal, or of one piece or built up of two or more pieces, as convenience and economy may prove best. The shape may also vary as here shown, with the core larger at the bottom than at the top so that it can easily be stripped or removed from the block after the concrete is cast and set. A different length block may be cast by using a different length core. As different strength blocks will be required for different purposes, the

size of the cores 7, 8 and 9 in proportion to the size of the block may be changed, leaving a larger or smaller air space in proportion to the size of the block as required for the use to which it is to be put.

Having thus described my invention I desire to secure by Letters Patent and claim:

1. In a building block mold the combination of a bottom; guide strips fastened on the edges of said bottom; side pieces resting on said bottom and contiguous said guide strips, to form a channel; end pieces in said channel held in place by pins projecting from said bottom and side pieces; spaced apart core blocks longitudinally disposed in said channel; partition blocks between said cores, with filling blocks to form recesses in the block case in said mold.

2. In a mold for building blocks the combination with a bottom; guide strips and side pieces; end pieces detachably held in the channel formed by said bottom and side pieces; spaced apart cores longitudinally disposed in said channel; partition members placed transversely in said channel and between said cores; filling blocks resting on said cores and vertically of the height of the upper edges of said side pieces; and metal sheets adapted for use adjacent the ends and sides of the individual block mold.

3. A mold for building blocks comprising a channel formed with a bottom and detachable sides and ends; cross bars to hold said sides in spaced relation to each other; semicylindrical cores longitudinally disposed in said channel; partition members between said cores; and filling blocks on said cores to form recesses in air recesses in the blocks which are to be molded in said form.

In testimony whereof I have affixed my signature.

CLARENCE E. KING.
